REFRIGERATION

Albert R. Thomas, Evansville, Ind., assignor to
 Servel, Inc., New York, N. Y., a corporation of
 Delaware

Application November 4, 1938, Serial No. 238,781

31 Claims. (Cl. 62—119.5)

My invention relates to refrigeration produced by evaporation of refrigerant fluid in the presence of auxiliary pressure equalizing fluid, and it is an object of the invention to provide method and apparatus whereby evaporation is more efficiently carried out. It is another object of the invention to provide more efficient cooling of a refrigeration system of this type utilizing evaporation of a plurality of fluids in the presence of each other. A further object is to effect a more efficient separation of the vapors produced by evaporation of a plurality of fluids in the presence of each other. Another object is to cool air for more satisfactory comfort conditions with the aid of refrigeration produced by fluid evaporation, more particularly, to automatically maintain a cooled air condition at a given differential with respect to atmospheric air.

The above, together with other objects and advantages of the invention, are more fully explained in the following description. The accompanying drawings to which reference is made in the description show in Fig. 1 a more or less diagrammatic view of a refrigeration system embodying the invention. Fig. 2 shows more or less diagrammatically a refrigeration system incorporating another embodiment of the invention. Fig. 3 shows more or less diagrammatically a further embodiment of the invention. Fig. 4 shows in vertical section apparatus for use in Fig. 3. Fig. 5 is a sectional view on line 5—5 of another part of the apparatus in Fig. 3; Fig. 6 is a detail sectional view on line 6—6 in Fig. 3; and Fig. 7 shows more or less diagrammatically another refrigeration system embodying the invention.

Referring to Fig. 1, a boiler or generator 10 is heated by an internal steam coil 11. Any suitable heater may be used. A circulation vessel 12 below the generator 10 is heated by a steam coil 13. The bottom of generator 10 is connected to the bottom of vessel 12 by a downward looped conduit 14. Above the generator 10 is an upper circulation vessel 15. The top of generator 10 is connected to the upper part of vessel 15 by a conduit 16. Lower vessel 12 is connected to upper vessel 15 by a conduit 17. The lower end of conduit 17 projects downward into vessel 12. One end of a generally horizontal conduit 18 is connected to the upper part of generator 10, and the other end of conduit 18 is connected to a vessel 19. Conduit 18 and vessel 19 together will be referred to as an analyzer.

The upper end of vessel 19 is connected by a conduit 21 to one end of a condenser 22. A part of conduit 21 sloping back toward the analyzer 55

is provided with heat radiation fins 23 forming an air cooled rectifier. Condenser 22 is illustrated as a water jacket around a part of conduit 21. A water inlet conduit 24 is connected to the lower end of the condenser jacket, and an outlet conduit 25 is connected to the upper end of the condenser jacket.

An evaporator 26 is shown as a finned pipe coil located in a thermally insulated compartment 10. 27. The lower end of evaporator 26 is connected by a downward looped conduit 28 to the outlet end of condenser 22. The upper end of evaporator 26 is connected by a conduit 29 to the lower part of an absorber 31.

15 The absorber is shown as comprising an upright cylindrical vessel within which is a cylindrically wound cooling coil 32. Coil 32 is located in an annular space formed between the outer absorber shell and an inner cylindrical form 33. 20 A water inlet conduit 34 is connected to the lower end of coil 32. The upper end of coil 32 is connected to conduit 24 which is the inlet conduit to condenser 22. On the upper end of the cylindrical form 33 is a circular trough or tray 35.

25 The edge of tray 35 is directly above the upper end of coil 32. A capillary siphon formed by wire mesh 36 extends from within the tray over the upper edge of the tray and downward above the coil 32. A liquid inlet conduit 37 discharges into tray 35. A liquid outlet conduit 38 is connected to the bottom of the absorber 31. A vent conduit 39 is connected from the upper part of absorber 31 to the upper end of conduit 28. A vapor outlet conduit 41 is connected to the top of absorber 31.

A second condenser 42 comprises a water cooling jacket around a conduit 43. This condenser jacket is provided with a water inlet connection 44 and a discharge conduit 45. The lower end of conduit 43 is connected to the upper part of a jacket 46. The jacket 46 is located around the open upper end of a conduit 47. Conduit 47 is looped downward and the other end is connected to the conduit 28 just below the lower end of evaporator 26. The absorber liquid inlet conduit 37 is connected to the lower part of jacket 46. The absorber vapor outlet conduit 41 is connected to the top of jacket 46.

The lower part of the upper circulation vessel 15 is connected by a conduit 48, the inner passage of a liquid heat exchanger 49 and a conduit 50 to the upper end of condenser 42. About a part of conduit 50 is located a water cooling jacket 51. The water outlet conduit 45 from condenser 42 is connected to jacket 51. A discharge conduit 52 is

connected to the other end of jacket 51. The absorber liquid outlet conduit 38 is connected to the outer passage of liquid heat exchanger 49 which is in turn connected by conduit 53 to the bottom of analyzer vessel 19.

The above described system is preferably formed of steel parts suitably welded together forming a system in which all parts are in open communication. By means of a suitable charging plug, not shown, in the absorber 31 there is introduced into the system a plurality of refrigerant fluids which are chemically inert with respect to each other. There is also introduced into the system a liquid absorbent for one of the refrigerant fluids. For instance, there may be introduced ammonia, propane and water. The ammonia and water are introduced in the form of a solution. The system is then hermetically sealed. Liquid will seek its own level in the lower parts of the apparatus and vapors of the liquids will fill the upper parts of the apparatus above the surface levels of liquid therein.

In operation, generator 10 and circulation vessel 12 are heated by steam in coils 11 and 13. Any liquid propane in these vessels will be caused to vaporize and the vapor will rise into the upper part of the apparatus. Ammonia which is dissolved in the water will be expelled from solution by heating. Vapor expelled from solution in vessel 12 accumulates in the upper part thereof, forcing the surface level of liquid therein downward until liquid is caused to flow upward through conduit 17 into upper vessel 15 by thermosyphon or vapor liquid lift action. This action may be improved by providing a small hole 20 in conduit 17 just above the lower end thereof in vessel 12.

Vapor expelled from solution in generator 10 accumulates in the upper end of the generator, in conduit 16, and in the upper part of vessel 15. When sufficient vapor has been expelled, it bubbles through liquid in analyzer conduit 18 and vessel 19. The vapor flows from the analyzer through conduit 21 to condenser 22. Ammonia vapor is condensed to liquid in condenser 22. The liquid flows downward into conduit 28 and accumulates in this conduit and in evaporator coil 26.

During operation of the system, cooling water flows through conduit 34, absorber cooling coil 32, conduit 24, condenser 22, and conduit 25. Cooling water also flows through conduit 44, condenser 42, conduit 45, liquid cooler 51, and conduit 52.

Weakened absorption liquid flows from vessel 15 through conduit 48, liquid heat exchanger 49 and conduit 50 into condenser 42. Ammonia vapor in condenser 42 is absorbed into the weakened solution so that propane vapor therein approaches the total pressure in the system and condenses to liquid. Ammonia solution and liquid propane flow from condenser 42 into jacket 46 and accumulate therein around the upper end of conduit 47. The liquid propane and ammonia solution are immiscible and the propane is lighter so that these liquids stratify with the propane on top.

The jacket 46 and the absorber liquid inlet 37 form a U-tube liquid trap of which the jacket 46 is one leg and conduit 37 is the other leg. The lower part of the jacket 46 and conduit 37 contain accumulated ammonia solution. The upper part of jacket 46 contains liquid propane. The column of liquid in jacket 46 comprising solution and liquid propane is lighter than an

equivalent column of solution only in conduit 37. Therefore liquid rises to a higher level in jacket 46 than in conduit 37. The overflow level in conduit 37 is below the level of the opening 5 of the upper end of conduit 47 in jacket 46 a distance which is the difference in levels of liquid in the different legs of this trap so that ammonia solution overflows from the upper end of conduit 37 into absorber 31, and liquid propane overflows from jacket 46 into the upper end of conduit 47.

Liquid propane accumulates in the downward looped conduit 47. The other end of conduit 47 is connected to conduit 28 just below the evaporator 26 so that liquid propane and liquid ammonia mix and enter evaporator 26 together. In evaporator 26, the propane and ammonia evaporate in the presence of each other. This evaporation produces a refrigeration effect for cooling compartment 27. The mixture of ammonia and propane vapors flows from the evaporator through conduit 29 into absorber 31.

Absorption solution discharges from inlet conduit 37 into tray 35. The liquid is withdrawn from tray 35 by the capillary siphon screen 36 and deposited onto the upper end of absorber cooling coil 32. The liquid flows downward over the outer surface of coil 32. Ammonia vapor is absorbed out of the mixture into solution in the absorption liquid. Resulting enriched solution accumulates in the bottom of absorber 31 and from there flows through conduit 38, liquid heat exchanger 49, and conduit 53 into the analyzer 18, 19 and thence back to the generator 10.

Propane vapor flows from the upper end of absorber 31 through conduit 41 into the upper end of jacket 46 and thence into condenser 42. Condenser 42 may be referred to as the propane condenser. Condenser 22 may be referred to as the ammonia condenser. At all places in the system the pressures are equal except for small differences due to trapping of vapor by liquid columns as in the vessel 12 for liquid circulation purposes, and in generator 10 for causing bubbling of vapors through liquid in the analyzer 18, 19. The pressure at any point is the sum of the pressures of ammonia, propane and water vapors. The purpose of analyzer 18, 19 and rectifier 23 is to minimize the amount of water vapor in the ammonia-propane vapors.

In the absorber 31, as ammonia vapor is absorbed into solution out of the mixture of ammonia and propane vapors, the partial pressure of the propane vapor increases. The vapors flowing through the absorber toward the propane condenser contain ammonia equal to or higher than the partial pressure of ammonia from the solution with which the vapors are in contact. This ammonia gas acts as an inert gas in the propane condenser and affects the condensation temperature of propane. As propane is condensed the partial pressure of the ammonia will increase, further lowering the condenser temperature. However, by flowing weak absorption solution through the propane condenser, as previously described, absorption of ammonia is carried out at or near the point of condensation, preventing increase in partial pressure of the ammonia and its effect on necessary condenser temperature.

Referring to Fig. 2, there is shown a system generally like that described in connection with Fig. 1. However, in this system there is provided a dual absorber and a modified form of propane condenser.

A generator 54 is heated by a burner 55. The

generator comprises an upright cylindrical casting through which extend a plurality of heating flues 56. The burner 55 is located below the lower ends of flues 56 in a heating chamber 57. From the lower part of generator 54 there extends downward a conduit 58. To the lower end of conduit 58 is connected the lower end of a conduit 59 having a coiled portion 60 located in the heating chamber 57. The upper end of conduit 59 is connected to the upper part of a circulation vessel 61. The upper part of generator 54 is connected by a conduit 62 to the upper part of vessel 61. An analyzer 63 is connected to the upper part of generator 54. Analyzer 63 is connected by a conduit 64, an air cooled rectifier 65 and a conduit 66 to an ammonia condenser 67. The ammonia condenser is connected by a conduit 68 to the lower header 69 of an evaporator or cooling element 70. The evaporator comprises a plurality of finned pipe coils connected between the lower header 69 and an upper header 71.

The absorber comprises a first part 72 and a second part 73. The absorber part 72 is like the absorber 31 described in connection with Fig. 1. The absorber coil 74 is connected by a conduit 75 to a coil 76 in the absorber part 73. Coil 76 is connected to a water inlet conduit 77, and coil 74 is connected to a water outlet conduit 78. Above the coil 74 is a liquid distributor 79 into which discharges a liquid inlet conduit 81. The inlet conduit 81 is connected to the lower end of a depending conduit 82 of which the upper end is connected to the upper part of absorber 73. The top of absorber 72 is connected by an upward looped conduit 83 to the lower part of absorber 73. In the lower part of absorber 73 above the open end of conduit 83 is a distributing plate or shell 84 which is an inverted perforated tray. The outlet end of ammonia condenser 67 is vented to the top of absorber 73 by a conduit 85.

The propane condenser 86 comprises a plurality of vertical tubes 87 connected between an upper header 88 and a lower header 89. The upper header 88 is connected to the top of an absorber vessel 91. The lower header 89 is connected to a conduit 92 which projects upward into the lower part of absorber vessel 91. The upper end of conduit 92 is protected by a spaced cover 93. In the upper part of absorber vessel 91 is a perforated liquid distributing plate 94. The absorber vessel 91 below the distributing plate 94 is filled with small particles such as Raschig rings 95. The bottom of absorber 91 is connected by a conduit 96 to the bottom of absorber 73. The lower header 89 is connected by a conduit 97 to the lower header 69 of the evaporator 70.

The circulation vessel 61 is connected by a conduit 98, inner passage of a liquid heat exchanger 99 and a conduit 101 to the upper part of absorber 91. The upper end of conduit 101 discharges in the absorber above the distributing plate 94. The bottom of absorber 72 is connected by a conduit 102, outer passage of the liquid heat exchanger 99 and conduit 103 to the analyzer 63.

The apparatus is constructed of steel parts welded together and is charged and hermetically sealed as described in connection with the apparatus shown in Fig. 1.

In operation, the burner 55 heats the coil 60 and generator 54. Cooling water is circulated through conduit 77, absorber coil 76, conduit 75,

absorber coil 74, and conduit 78. The ammonia condenser 67 and the propane condenser 86 may be provided with fins (not shown) for cooling by air, or with jackets (not shown) for water cooling.

Ammonia vapor is expelled from solution in the generator and in coil 60. Vapor expelled in coil 60 causes upward flow of liquid from the lower part of generator 54 into the circulation vessel 61 by vapor lift action. More than one conduit 59 and coil 60 may be provided. In larger systems it will be found desirable to provide two or more vapor lift conduits for carrying out the upward flow of weakened absorption solution.

Vapor expelled from solution in the generator 54 accumulates in the upper end of the generator, in conduit 62, and the upper part of vessel 61. The vapor escapes from the upper end of generator 54 by bubbling through liquid in the analyzer 63. Ammonia vapor flows from the analyzer through conduit 64, rectifier 65, and conduit 66 to the condenser 67. Ammonia vapor is condensed to liquid in condenser 67. The liquid ammonia flows from condenser 67 through conduit 68 into the evaporator 70.

Liquid propane flows from the propane condenser 86 through conduit 97 into the evaporator 70. In the lower header 69 and in the coils 70 the liquid ammonia and liquid propane mix together and evaporate in the presence of each other. The resulting mixture of ammonia and propane vapors flows from the upper header 71 through conduit 80 into the lower part of absorber 72.

Weakened absorption liquid flows from circulation vessel 61 through conduit 98, heat exchanger 99, and conduit 101 into the propane condenser-absorber 91. The weak solution is distributed by perforated plate 94 and flows downward over the Raschig rings or other suitable particles 95 keeping these particles wet. In the lower part of absorber 91 absorption solution flows through conduit 96 into absorber 73. The liquid fills absorber 73 to the point of overflow into conduit 82. Liquid overflows from absorber 73 into conduit 82 and flows from the lower end of conduit 82 through conduit 81 into the distributor 79 and the upper part of absorber 72. Absorption liquid is distributed onto the absorber coil 74 and flows downward over the outer surface of this coil.

In absorber 72, ammonia vapor is absorbed out of the vapor mixture into solution flowing downward on coil 74. The enriched solution accumulates in the lower part of absorber 72 and flows from there through conduit 102, liquid heat exchanger 99, conduit 103, and analyzer 63 back to the generator 54.

Vapors pass from the top of absorber 72 through conduit 83 into the lower part of absorber 73. Vapors issuing from the open end of conduit 83 spread beneath the distributing plate 84 and bubble upward through the openings in plate 84 and through the body of absorption liquid in this absorber. From the upper part of absorber 73 vapor flows through conduit 90 into the propane condenser 86. In the propane condenser-absorber 91, the vapors pass over the wet surfaces of the particles 95 and ammonia vapor is absorbed into weak absorption solution.

Propane vapor condenses to liquid in the propane condenser and drains downward in the vertical tubes 87 into the header 89 and thence into conduit 97. A local circulation occurs in

the propane condenser. The direction of this circulation is upward in tubes 87 and downward in the absorber 91 and conduit 92. Vapor becomes less dense in the tubes 87 due to condensation of propane and heavier in absorber 91 due to removal of ammonia vapor. This circulation of vapor from the propane condenser through the absorber 91 keeps the partial pressure of ammonia in the propane condenser close to equilibrium with the partial pressure of ammonia from the weakened solution in the absorber 91.

In Fig. 3 is shown an air cooled system. A generator 105 is heated by a burner 106. The lower part of the generator is provided with a downward conduit 107. One or more vapor lift conduits 108 is connected from the lower end of conduit 107 to the upper part of a circulation vessel 109. Each vapor lift conduit is formed with a coil portion 110 heated by burner 106. The top of generator 105 is connected by a conduit 111 to the upper part of circulation vessel 109. An analyzer 112 is connected to the upper part of generator 105.

The analyzer 112 is connected by a conduit 113 to an air cooled rectifier 114 which is in turn connected by a conduit 115 to the upper end of a condenser 116. The lower end of condenser 116 is connected by a vessel 117 and a conduit 118 to a lower header 119 of an evaporator 120.

Referring to Figs. 3, 5 and 6, the evaporator 120 consists of the lower header 119 and an upper header 121 between which are connected a plurality of flat pipe coils 122. The pipe coils 122 are provided with heat transfer fins. The lower part of header 121 is connected to the upper part of header 119 by a conduit 123. The lower end of each of the pipe coils 122 extends downward into the lower header 119 and is provided with an upright slot 124.

The upper part of header 121 is connected by a conduit 125 to the upper part of an absorber vessel 126. The upper part of vessel 126 is connected by a conduit 127 to the lower end of an absorber coil 128. The coil 128 is provided with heat transfer fins. The upper end of absorber coil 128 is connected by a conduit 129 to the upper end of a condenser 130. The lower end of condenser 130 is connected to the upper part of jacket 131 which is arranged around the upper end of a conduit 133. The lower end of conduit 133 is connected to the lower evaporator header 119. The lower part of jacket 131 is connected by a conduit 134 to conduit 129. The connection of conduit 134 to conduit 129 is made at a level which is slightly lower than the level of the opening in the upper end of conduit 133 in jacket 131. The purpose of this is explained below.

The top of vessel 117 at the lower end of condenser 116 is connected by a vent conduit 135 to the upper part of absorber vessel 126.

The lower part of circulation vessel 109 is connected by a conduit 136, the inner passage of a liquid heat exchanger 137, and conduit 138 to the upper part of condenser 130. The bottom of absorber vessel 126 is connected by a conduit 139, outer passage of the liquid heat exchanger 137, and conduit 140 to the analyzer 112.

The system is charged with propane, ammonia, and water, or other suitable fluids as previously set forth. Provision is made for causing atmospheric air to flow in a path that includes first condenser 116, then condenser 130, next absorber 128, and then rectifier 114. In order not to complicate the drawing, this provision is indicated in dotted outline and direction arrows in Fig. 3.

The dotted outline indicates an air tunnel and a blower for causing flow of air through the tunnel. Provision is also made for spraying water onto the condensers 116 and 130. These water sprays are indicated at 141 in Fig. 3.

In Fig. 4 there is shown mostly in vertical section an actual arrangement of parts for use in the dotted outline section of Fig. 3. Referring to Fig. 4, pipes 116a constitute a first condenser. Pipes 130a constitute a second condenser. These condensers are arranged in the order mentioned in an air passage 142 between the air inlet end 143 and the connection of the other end of the passage to the intake of a blower 144. Between the condenser coil 130a and blower 144 are zig-zag baffle plates 145. Above the condenser coils 116a and 130a are water spray heads 141a having a water supply conduit 146. Below the condenser coils 116a and 130a and the baffles 145 is a trough or sump 147 having a discharge conduit 148. A liquid pump, not shown, may be provided for pumping water from conduit 148 into conduit 146. Make-up water, the connection for which is not shown, is also supplied to conduit 146.

The discharge side of blower 144 is connected to one end of an air passage 149. A finned pipe coil 128a and a smaller finned pipe coil 114a are located in air passage 149 in series respectively between the discharge side of blower 144 and the air exit 150.

Referring to Figs. 3 and 4, coil 130a may be connected in the system shown in Fig. 3 in the place of coil 130. Coil 116a may be connected in the system in the place of coil 116. Coil 128a may be connected in the system in the place of absorber coil 128. Coil 114a may be connected in the system in the place of rectifier coil 114.

In operation of the system, burner 106 is turned on and heats the coil or coils 110 and generator 105. Blower 144 is operated to cause air to flow in series respectively over condenser coil 116, 116a, condenser coil 130, 130a, absorber coil 128, 128a, and rectifier coil 114, 114a. Water is discharged from spray heads 141, 141a to wet the condenser coils. Free water is disentrained from the air stream by baffles 145. Excess water accumulates in sump 147 and is drawn from there through conduit 148 and preferably returned to the spray heads.

Water on the outer surfaces of the condenser coils evaporates and diffuses into the air causing cooling of the condenser coils toward the wet bulb temperatures of the air. The absorber coil 128, 128a, is cooled toward the dry bulb temperature of air from the blower 144. The rectifier coil 114, 114a is cooled toward the dry bulb temperature of air coming from the absorber.

Heat from the burner 106 causes expulsion of ammonia vapor from solution in water in the coil or coils 110 and generator 105. Vapor expelled from solution in coil or coils 110 causes upward flow of weakened absorption liquid from the lower part of generator 105 through conduit 108 to the circulation vessel 109 by vapor lift action. Vapor expelled from solution in generator 105 accumulates in the upper part of the generator, in conduit 111 and in the upper part of vessel 109. This accumulated vapor presses liquid downward in generator 105 until the vapor bubbles through liquid in analyzer 112.

Ammonia vapor flows from analyzer 112 through conduit 113 and rectifier 114 to condenser 116. Condenser 116 will be referred to as the ammonia condenser. Due to the previously

described cooling, ammonia vapor condenses to liquid in condenser 116. The liquid ammonia flows from the lower end of the condenser into the vessel 117 and thence through conduit 118 into evaporator 120.

Weakened absorption liquid flows from vessel 109 through conduit 136, liquid heat exchanger 137, and conduit 138 into the upper part of condenser 130. The absorption liquid flows downward in condenser 130 and absorbs into solution ammonia vapor. This reduces the partial pressure of ammonia vapor to that of vapor from the weak solution at the temperature of the condenser 130. Decrease in the partial pressure of ammonia is accompanied by increase in partial pressure of propane vapor toward the total pressure in the system so that the propane vapor condenses to liquid due to the previously described cooling of condenser 130.

Absorption solution and liquid propane flow from the lower end of condenser 130 into the jacket 131 and accumulate in this jacket and in conduit 134. Liquid propane and the water solution of ammonia are immiscible so that they separate and stratify in jacket 131 with the liquid propane floating on the surface of the solution. Liquid propane is lighter than the water solution of ammonia so that a column of liquid comprising both is lighter than a column of liquid comprising only solution. For this reason the column of liquid in jacket 131 is lighter than the column of liquid in conduit 134 and therefore stands to a higher level. The surface level of liquid increases in both jacket 131 and conduit 134 until solution overflows from conduit 134 into the upper end of absorber coil 128, and liquid propane overflows into the upper end of conduit 133. The liquid propane flows through conduit 133 into the evaporator 120.

The ammonia feed conduit 118 and the propane feed conduit 133 form with the evaporator 120 two liquid traps of which the evaporator is a common leg. Liquid propane accumulates in conduit 133. Liquid ammonia accumulates in conduit 118. Both ammonia and propane accumulate in the evaporator 120, filling the lower header 119, the coils 122, and conduit 123. In the evaporator 120, the liquid propane and liquid ammonia come into contact with each other first in the lower header 119. In the presence of each other, the ammonia and propane evaporate, producing a precooling of liquid in the header before it enters the pipe coils 122. In the coils 122, ammonia and propane evaporate in the presence of each other, producing a refrigeration effect for cooling of air in chamber 132 in which the evaporator is situated. A blower, not shown, or other suitable means may be used for causing a forced flow of air over the evaporator coils. Vapors formed in the header 119 and in the pipe coils 122 rise through the pipe coils into the upper header 121. This upward flow of vapor causes circulation of liquid in the evaporator from the lower header 119 upward through the coils 122 into the upper header 121 and thence down through conduit 123 back to the lower header 119. More than one conduit 123 may be provided. This circulation of liquid keeps the inside surfaces of the evaporator coils wet, resulting in good heat transfer to the liquid. This liquid circulation also maintains a fine intermixture of liquid propane and liquid ammonia, overcoming the tendency of these liquids to stratify into separate layers. The fine intermixture of the two fluids results in large inter-

facial contact and short diffusion distance. The purpose of the slots 124 in the lower ends of coils 122, as best seen in Figs. 5 and 6, is to provide for introduction of liquid from the header 119 into the tubes 122 from all levels in the header 119 so that if propane stratifies and floats in the upper part of header 119 it will be nevertheless carried into the coils 122 along with liquid ammonia by vapors formed in the header 119 and escaping therefrom through the slots 124 into the tubes 122.

The mixture of propane and ammonia vapors flows from the upper header 121 through conduit 125 into the absorber vessel 126 and thence through conduit 127 into the absorber coil 128. Ammonia vapor is absorbed into solution flowing downward in coil 128. Propane vapor flows from the upper end of coil 128 through conduit 129 into the propane condenser 130. Enriched solution flows from absorber coil 128 through conduit 127 into absorber vessel 126. Solution flows from vessel 126 through conduit 139, outer passage of the liquid heat exchanger 137 and conduit 140 to the analyzer 112 and thence into the generator 105.

The condensation temperature in the propane condenser 130 is somewhat above that in the ammonia condenser 116. For instance, with a temperature of 50° F. in the evaporator 120, the condensation temperature in the propane condenser is about 7° above that in the ammonia condenser, the ammonia condensation temperature being about 90° F. and the propane condensation temperature being about 97° F. At this evaporator temperature the absorber and rectifier heat can be rejected at higher temperatures. For these reasons, the stream of cooling air is caused to flow, as previously described, over first the ammonia condenser 116, then the propane condenser 130, next the absorber 126, and then the rectifier 114.

It has been found possible to condense at a temperature 10° F. above the wet bulb temperature of the air by using a so-called evaporative condenser. As illustrated diagrammatically in Fig. 3, water from nozzles 141 is sprayed downward over the condenser coils 116 and 130 to keep the outer surfaces of these coils wet so that the condenser temperature is dependent upon the wet bulb temperature of the cooling air. Due to the available temperature for heat rejection at the condensers, the evaporator temperature will be about 40° F. below the temperature of the ammonia condenser. This characteristic of the system is advantageous in air conditioning, in satisfying inherently the present trend toward maintaining inside air conditions at a certain differential below the conditions of the outside air. The wet bulb temperature represents more than any other single factor the comfort condition of atmospheric air, and with this system it is possible to automatically obtain an inside condition at a given differential below the outside wet bulb temperature. Heretofore this has only been accomplished by differential thermostats or other complicated controls.

Referring to Fig. 7, the system is provided with two identical generators 152 and 153 heated by burners 154 and 155. Each generator has an analyzer 156 and 157 and a rectifier 158 and 159. Each generator also has associated therewith a vapor liquid lift conduit 160 and 161 connected to circulation vessels 162 and 163. The upper parts of the generators are connected

to the circulation vessels by conduits 164 and 165. A liquid heat exchanger has a portion 166 coiled about generator 152. A liquid heat exchanger 167 has a portion coiled about generator 153. There are two weak liquid cooling coils 168 and 169. There are two ammonia condensers 170 and 171. There is an absorber-liquid heat exchanger 172. The liquid heat exchangers, the ammonia condensers, and the weak liquid coolers are formed by coiled concentric tubes.

Circulation vessels 162 and 163 are connected by conduits 173 and 174 respectively to liquid heat exchangers 166 and 167, which in turn are respectively connected by conduits 175 and 176 to weak liquid coolers 168 and 169. Rectifiers 158 and 159 are provided with water cooling coils 177 and 178. The rectifiers are connected by conduits 179 and 180 to a vessel 181 which is in turn connected by conduits 182 and 183 to ammonia condensers 170 and 171.

The lower ends of condensers 170 and 171 are connected by conduits 184 and 185 to a vessel 186 which is in turn connected by conduit 187 to a vessel 188. The bottom of vessel 188 is connected by a conduit 189 to the lower header 190 of an evaporator 191.

The evaporator 191 comprises a lower header 190 and an upper header 192 between which is connected one or more finned pipe coils 193. The upper header 192 is connected by a conduit 194 to a vessel 195. The bottom of vessel 195 is connected by a conduit 196 to a lower header 190. The top of vessel 195 is connected by an upward looped conduit 197 to the lower part of an absorber 198.

Absorber 198 comprises a vessel containing water cooling coils 199. In the lower part of the vessel is a perforated distributing plate 200. The end of conduit 197 projects into absorber 198 and is open beneath the center of plate 200. The bottom of absorber 198 is connected by a conduit 201, outer passage of liquid heat exchanger 166, and conduit 202 to analyzer 156. The bottom of absorber 198 is connected by a conduit 203, outer passage of liquid heat exchanger 167, and conduit 204 to analyzer 157. The top of absorber 198 is connected by an upward looped conduit 205 to the lower part of a second absorber 206. The bottom of absorber 206 is connected through a conduit 207, a cooler 208, and a conduit 209 to an intermediate part of absorber 198.

Absorber 206 is filled nearly to the top with small particles such as Raschig rings. Above the mass of particles is a perforated distributing plate 210. One end of a weak liquid line 211 is connected to the upper part of absorber 206 and discharges onto the distributing plate 210. The other end of conduit 211 is connected to weak liquid cooler 169. A vent line 212 is connected from the top of absorber 206 to the top of vessel 188. The top of absorber 206 is connected by a conduit 213 to the lower part of a condenser 214. An intermediate part of absorber 206 is connected by a downward looped conduit 215 to the bottom of a vessel 216.

The upper part of vessel 216 is connected by a downward looped conduit 217 to the bottom of a vessel 218. The top of vessel 216 is connected by an upward looped conduit 219 to the top of vessel 218. The upper part of vessel 218 is connected by a conduit 220 to the upper part of condenser 214. A closed end conduit 221 is connected to the upper part of vessel 218 at the same level as the connection thereto of conduit

220. The bottom of conduit 221 is connected by a conduit 222 to the lower evaporator header 190. Vessel 218 is connected from a point just below the connection thereto of conduit 220 by a downward looped conduit 223 to the bottom of condenser 214.

Condenser 214 is a closed vessel containing water cooling coils 224. Above the coils 224 is a liquid distributing tray 225. The upper part of condenser 214 is connected by a conduit 226 to weak liquid cooler 168. The end of conduit 226 projects into the upper part of condenser 214 and discharges into the distributing tray 225. The end of conduit 213 projects into the lower part of condenser 214 and is provided with openings below the cooling coil 224.

A water inlet conduit 228 is connected by conduits 229 and 230 to one end of the water jackets of weak liquid coolers 128 and 129. Water pipes 231, 232, 233, 234 and 235 connect the liquid coolers 168 and 169 to the ammonia condensers 170 and 171. Water pipes 236, 237 and 238 connect the ammonia condensers 170 and 171 to the lower end of cooling coil 224 in the propane condenser 214. The upper end of cooling coil 224 is connected by a conduit 239 to the lower end of cooling coil 199 in absorber 198. The upper end of cooling coil 199 is connected by a conduit 240 to one end of the intermediate absorber cooler 208. The other end of cooler 208 is connected by a water pipe 241 to the upper ends of the rectifier cooling coils 177 and 178. The lower ends of coils 177 and 178 are connected by conduits 242 and 243 to a water discharge conduit 245.

The system is charged with propane, ammonia, and water. A charging valve, not shown, may be provided in the absorber 198 at the surface level of liquid shown therein so that the liquid can be adjusted to this level.

In operation of the system, burners 154 and 155 heat generators 152 and 153. Water entering through conduit 228 flows through the previously described pipe connections respectively through weak liquid coolers 168 and 169, ammonia condensers 170 and 171, propane condenser cooling coil 224, absorber cooling coil 199, intermediate absorber liquid cooler 208, and rectifier cooling coils 177 and 178.

Ammonia vapor is expelled from solution in generators 152 and 153 and in the coiled portions of conduits 160 and 161. Vapor expelled in conduits 160 and 161 causes upward flow of liquid through these conduits from the generators into the circulation vessels 162 and 163. Vapor expelled from solution in the generators 152 and 153 bubbles through liquid in the analyzers 156 and 157 and then flows through rectifiers 158 and 159, conduits 179 and 180, vessel 181, and conduits 182 and 183 to the ammonia condensers 170 and 171. Ammonia vapor is condensed to liquid in the condensers 170 and 171. Liquid ammonia flows from the condensers through conduits 184 and 185, vessel 186, conduit 187, vessel 188, and conduit 189 into the evaporator 191.

Weakened absorption liquid flows from circulation vessel 162 through conduit 173, inner passage of liquid heat exchanger 166, conduit 175, weak liquid cooler 168, and conduit 226 into the distributing tray 225 in the upper part of propane condenser 214.

Weakened absorption liquid flows from circulation vessel 163 through conduit 174, inner passage of liquid heat exchanger 167, conduit 176,

weak liquid cooler 169, and conduit 211 into the distributing plate 210 in the upper part of absorber 206.

In the propane condenser 214, absorption liquid overflows tray 225 and descends on the surfaces of the cooling coils 224. Ammonia vapor is absorbed into solution in the descending absorption liquid, reducing and maintaining the partial pressure of ammonia in the propane condenser so that it is at a value which is substantially the partial pressure of ammonia vapor from the weak solution at the propane condenser temperature. The liquid accumulates in condenser 214 and conduit 223 and the surface level rises to the overflow points in vessels 218 and 216. Due to the reduction in partial pressure of ammonia in condenser 214, the partial pressure of propane increases toward the total pressure in the system and then condenses to liquid. The liquid propane is immiscible and separates from the solution and floats on the surface in the condenser 214. Liquid overflows from condenser 214 through conduits 220 and 223 into vessel 218. Liquid overflows from vessel 218 through conduit 217 into vessel 216. Liquid also overflows from vessel 218 through conduit 221 and conduit 222. Conduits 223 and 217 are connected to the bottoms of condenser 214 and vessel 218 so that liquid flowing through these conduits is solution from which liquid propane is separated by stratification. Liquid which overflows from condenser 224 through conduit 220 into vessel 218 and which overflows from vessel 218 through conduits 221 and 222 is liquid propane floating on the surface of solution. Separation by stratification occurs in both the propane condenser 214 and vessel 218. Stratification in vessel 218 separates from solution any liquid propane that may enter vessel 218 through conduit 223 from the condenser.

Liquid propane which overflows into conduit 222 enters evaporator 191 and there joins liquid ammonia. The liquid propane and liquid ammonia mix in header 190 and coils 193 and evaporate in the presence of each other, producing a refrigeration effect, as previously described in connection with other modifications of this system. The vapor causes upward flow of liquid from lower header 190 through coils 193 to upper header 192. Liquid returns from the upper header through conduit 194, vessel 195 and conduit 196 to the lower header 190. This circulation of liquid keeps the evaporator coils wet inward for efficient heat transfer, and the ebullition due to formation of gas below the surface thereof keeps the propane and ammonia liquids intimately mixed, producing large interfacial contact and small diffusion distance.

A mixture of vapors from the evaporator 191 flows through conduit 197 into the lower part of the bubble type absorber 198. Vapors issuing from the open end of conduit 197 spread beneath the perforated plate 200 and pass upward through the plate in the form of bubbles which rise to the surface of the liquid and enter the top of this absorber. In the bubble absorber 198, the strongest vapors meet the strongest solution at the highest temperature in the absorber system. Most of the ammonia vapor is absorbed in the bubble absorber 198. About 70 to 80% of the absorption that takes place occurs in this bubble absorber.

The vapor mixture, with the partial pressure of ammonia greatly reduced, flows from the bubble absorber 198 through conduit 205 into the lower end of the packed absorber tower 206. The

weak absorption liquid entering the top of the absorber tower 206 through conduit 211 is distributed by plate 210 and flows downward over the surfaces of the material in the upper part of this absorber. Solution from the propane condenser enters the absorber tower 206 through conduit 215 and flows downward over the packing in the lower part of this absorber. The vapors enter the lower end of the absorber tower 206, rise through the packed material in contact with the surfaces thereof wet by absorption liquid, and further absorption of ammonia vapor takes place. Vapor containing only a very small amount of ammonia, 5% or less, flows from the upper end of absorber tower 206 through conduit 213 into the lower part of propane condenser 214. The vapor issues through the holes in the end of conduit 213 and bubbles upward through liquid in the condenser 214. The bubbles rising through the cooling liquid in condenser 214 collapse due to the condensation of propane and the absorption of the residual ammonia. The propane condensed to liquid stratifies and is separated from the solution as previously described. Absorption liquid flows from the bottom of the absorber tower 206 through conduit 207, cooler 208, and conduit 209 into the bubble absorber 198. Solution flows from the bubble absorber 198 through conduits 201 and 203, outer passages of liquid heat exchangers 166 and 167, and conduits 202 and 204 into the analyzers 156 and 157, and thence back into the generators 152 and 153.

During operation of this system, the pressure from the evaporator 191 is higher than that in the upper part of condenser 214 by the hydrostatic head of liquid standing to the levels shown in absorber 198 and condenser 214. In returning the propane condensate from the condenser 214 to the higher pressure of evaporator 191, an overbalancing column of liquid is formed to the level indicated in conduit 222. The pressure from evaporator 191 is also higher than that in the condensers 170 and 171 by the hydrostatic head of liquid in the absorber 198. In returning the ammonia condensate from the condensers 170 and 171 to the higher pressure of evaporator 191, an overbalancing column of liquid is formed to the level indicated in vessel 188 and conduit 189.

What is claimed is:

1. A method of refrigeration which includes evaporating a plurality of refrigerant fluids in the presence of each other, separating one refrigerant fluid from another in the resulting vapor mixture by absorption into a liquid, separating said first refrigerant fluid from solution by distillation, condensing said second refrigerant fluid to liquid, bringing said absorption liquid into the presence of said second refrigerant fluid while the latter is undergoing condensation, and dissipating the heat of said condensation at a temperature lower than that at which the heat of said absorption is dissipated by first transferring heat of condensation to a body of cooling fluid and then transferring heat of absorption to said body of cooling fluid.

2. A method of refrigeration as set forth in claim 1 in which heat of condensation from said distillation step is first transferred to said body of cooling fluid.

3. A method of refrigeration as set forth in claim 1 in which heat of rectification from said distillation process is last transferred to said body of cooling fluid.

4. A method of refrigeration as set forth in claim 1 in which said refrigerant fluids are am-

monia and propane respectively and said absorption liquid is water.

5. A refrigeration system having a first circuit comprising a generator, condenser, evaporator, and absorber, and a second circuit comprising said evaporator, said absorber, and a second condenser, said system containing a plurality of refrigerant fluids such as ammonia and propane, and a liquid absorbent for one of said refrigerants such as water, said circuits being connected so that absorption liquid flowing toward the absorber in said first circuit flows through the condenser in said second circuit, and means for separating liquid refrigerant condensed in said second condenser from the absorption liquid. 10

6. A refrigeration system as set forth in claim 5 in which said first circuit includes a plurality of absorbers connected in series.

7. A refrigeration system as set forth in claim 5 in which said first circuit includes a plurality of absorbers connected in series, one of said absorbers being of a type in which vapors bubble through liquid.

8. A refrigeration system as set forth in claim 5 in which said first circuit includes a plurality of absorbers, and the circuits are connected and arranged so that only a portion of said absorption liquid flows through the condenser in said second circuit. 25

9. A refrigeration system as set forth in claim 5 in which vapor bubbles through liquid in the condenser in said second circuit.

10. In a method of refrigeration which includes evaporation of a plurality of fluids in the presence of each other, that improvement which consists in bringing the fluids together in liquid phase and forming thereof one or more bodies having relatively small horizontal cross-sectional area so that ebullition due to formation of vapors below the surface level of the liquid will keep the several liquids thoroughly mixed and thereby have large interfacial contact surfaces and short vapor diffusion distances. 30

11. Apparatus for carrying out the method of refrigeration as set forth in claim 10 including an evaporator having one or more pipes or pipe coils of relatively small diameter for forming said body or bodies of liquid, and constructed and arranged for continuous upward flow of vapor therein.

12. In a method of refrigeration which includes evaporation of a plurality of fluids in the presence of each other, that improvement which consists in mixing the fluids together in liquid phase to effect evaporation thereof, and utilizing the resulting vapors to cause ebullition and further thorough mixing of the liquids and also to cause upward flow of the liquids by vapor lift action to effect good heat transfer to the liquid.

13. Apparatus for carrying out the method of refrigeration set forth in claim 12 including an evaporator comprising one or more pipes or pipe coils having a relatively small internal diameter and arranged for continuous upward flow of vapor and liquid therein.

14. Apparatus for carrying out the method of refrigeration set forth in claim 12 including an evaporator having upper and lower headers connected by one or more pipes or pipe coils, the lower ends of said pipes or pipe coils extending downward into the lower header and having upright slots therein so that liquid may enter from different levels in the lower header.

15. Apparatus for carrying out the method of refrigeration as set forth in claim 12 including an

evaporator comprising upper and lower headers connected by one or more pipes or pipe coils arranged for upward flow of vapor and liquid therethrough from the lower header to the upper header, and one or more conduits for return flow of liquid from the upper header to the lower header. 5

16. An evaporator for use in a refrigeration system utilizing evaporation of several fluids in the presence of each other, and including a vessel, connections for admitting several fluids in liquid phase to said vessel, and a conduit extending upward from said vessel, the lower end of said conduit communicating with said vessel at a plurality of levels therein.

17. An evaporator as set forth in claim 16 which also includes a conduit for return of liquid from the upper end of said upward extending conduit to said vessel.

18. An evaporator as set forth in claim 16 which also includes a separating vessel for vapor and liquid at the upper end of said upward extending conduit, and a further conduit for flow of liquid from said separating vessel to said lower vessel.

19. In a method of refrigeration which includes evaporation of a plurality of fluids in the presence of each other, that improvement which consists in bringing the fluids together in liquid phase to effect evaporation thereof, and utilizing the resulting vapor to cause upward flow of the liquids in the presence of each other.

20. A method of refrigeration which includes bringing together a plurality of fluids in liquid phase to effect evaporation of the liquids in the presence of each other to produce a refrigeration effect, and causing upward flow of the liquids in one place and downward flow of the liquids in another place, and withdrawing vapor from the presence of the liquid intermediate said places. 35

21. A method of refrigeration which includes condensing refrigerant fluid to liquid at a certain pressure, evaporating said liquid refrigerant in the presence of another fluid at substantially the same total pressure as said condensing pressure, causing the liquid refrigerant to flow upward in one place and downward in another place, and withdrawing vapor from the presence of the liquid intermediate said places. 45

22. A refrigeration system having a place of condensation, a place of evaporation, means for conducting liquid refrigerant from said place of condensation to said place of evaporation, means for conducting a pressure equalizing fluid to said place of evaporation to equalize the pressure at said place of evaporation and said place of condensation, means for causing liquid refrigerant to circulate in a definite orbit in said place of evaporation, and means to withdraw vapor from the presence of liquid in said orbit. 50

23. Refrigeration apparatus including a condenser, an evaporator having one or more conduits providing one or more definite orbits for fluid circulation, a conduit for conducting liquid refrigerant from said condenser to said evaporator, a conduit for admitting an auxiliary pressure equalizing fluid to said evaporator to equalize the pressures in said evaporator and said condenser, and a conduit for withdrawing vapor from said evaporator, the one or more orbit forming conduits being sufficiently narrow so that vapor formed by evaporation of liquid causes circulation of liquid therein. 55

24. A refrigeration system comprising a generator, a condenser, an evaporator, an absorber, 60

70

said generator and absorber being connected for circulation of absorption liquid therethrough and therebetween, said condenser being connected to receive vapor from said generator and deliver liquid to said evaporator, and said absorber being connected to receive vapor from said evaporator, a second condenser connected to receive vapor from said absorber, a vessel connected to receive liquid from said second condenser, an overflow conduit from the lower part of said vessel to said absorber, an overflow conduit from the upper part of said vessel to said evaporator, said second condenser, said vessel, and said overflow conduit to the absorber being connected in said generator-absorber circuit in the path of flow of liquid from said generator to said absorber, said system containing ammonia, water, and propane.

25. A refrigeration system comprising a generator, two condensers, an evaporator and two absorbers, one of said condensers being connected to receive vapor from said generator and deliver liquid to said evaporator, said generator being connected for circulation of liquid therethrough said absorbers in series, one of said absorbers being connected with the other of said condensers for circulation of vapor therethrough and therebetween, said second condenser being connected for delivery of liquid to said evaporator, connections for flow of vapor from said evaporator to the other of said absorbers and thence to said first absorber, and said system containing ammonia, water and propane.

26. In a refrigeration system having a still-evaporator-absorber circuit for ammonia and a condenser-evaporator-absorber circuit for propane, a second absorber connected to receive weakened absorption liquid flowing in said first circuit and connected with the condenser in said second circuit for circulation of vapor therethrough and therebetween.

27. A refrigeration system including an evaporator, a plurality of condensers, an absorber, and a generator interconnected to form a still-evaporator-absorber circuit and a condenser-evaporator-absorber circuit, means for flowing atmospheric air first in heat transfer relation with said condensers and then in heat transfer relation with said absorber, said condensers being cooled by evaporation of water in the presence of said air so that said evaporator will be automatically maintained at a temperature which is at a certain value below that of the wet bulb temperature of the atmosphere.

28. A refrigeration system as set forth in claim 27 also including a rectifier connected in said still circuit and arranged to be cooled last by said air. 55

29. A refrigeration system for conditioning air and comprising an evaporator arranged for cooling of air to be conditioned, an absorber, said evaporator and absorber being included in both a still-evaporator-absorber circuit and a condenser-evaporator-absorber circuit, said system containing propane and ammonia which evaporate in the presence of each other in said evaporator at a temperature which is directly proportional to the temperature of the condensing portion of said still-evaporator-absorber circuit, and coolers for the heat rejecting parts of said system, the cooler for said condensing portion utilizing evaporation of water in the presence of atmospheric air so that said evaporator will be automatically maintained at a temperature which is directly proportional to the wet bulb temperature of the atmosphere.

30. A refrigeration system for conditioning air and comprising a first circuit having a generator, a first condenser, an evaporator, and an absorber, a second circuit having a second condenser and including said evaporator and absorber, said system containing a plurality of refrigerant fluids which evaporate in the presence of each other in said evaporator at a temperature which is directly proportional to the temperature of said first condenser, and coolers for the heat rejecting parts of the system, the cooler for said first condenser utilizing evaporation of water in the presence of atmospheric air so that said evaporator will be automatically maintained at a temperature which is directly proportional to the wet bulb temperature of the atmosphere.

31. A method of refrigeration which includes evaporating a plurality of refrigerant liquids in the presence of each other, utilizing the refrigerating effects thus produced to cool air to be conditioned, absorbing one of said refrigerants out of the resulting vapor mixture, condensing another of said refrigerant vapors to liquid state for re-use in said evaporation step, expelling the absorbed refrigerant from the absorbent, condensing the expelled refrigerant from vaporous to liquid state for re-use in said evaporation step, said evaporation taking place at a temperature which is directly proportional to the temperature at which said expelled refrigerant is condensed, and carrying out condensation of the expelled refrigerant by heat transfer to water evaporating in the presence of atmospheric air so that the evaporation step will take place at a temperature which is directly proportional to the wet bulb temperature of the atmosphere.

ALBERT R. THOMAS.
